UNITED STATES PATENT OFFICE.

ETHAN I. DODDS AND JOHN ROGERS FLANNERY, OF PITTSBURGH, PENNSYLVANIA,
ASSIGNORS TO FLANNERY BOLT COMPANY, OF PITTSBURGH, PENNSYLVANIA.

METHOD OF MAKING AND INSTALLING STAYBOLT STRUCTURES IN BOILERS.

1,373,058.

Specification of Letters Patent. Patented Mar. 29, 1921.

Original application filed September 10, 1919, Serial No. 322,871. Divided and this application filed April 8, 1920. Serial No. 372,291.

To all whom it may concern:

Be it known that we, ETHAN I. DODDS and JOHN ROGERS FLANNERY, citizens of the United States, and residents of Pittsburgh, 5 in the county of Allegheny and State of Pennsylvania, have invented certain new and useful Improvements in Methods of Making and Installing Staybolt Structures in Boilers; and we do hereby declare the following to be a full, clear, and exact description of the invention, such as will enable others skilled in the art to which it appertains to make and use the same.

This invention relates to improvements in 15 the method of making and installing staybolt structures in boilers,—the same being a division of application for patent filed by us on the 10th day of September, 1919, Serial No. 322,871,—one object of our present invention being to provide a simple and efficient method of combining the head of a staybolt and its bearing member so that said head shall be permanently inclosed within 20 the bearing member but be capable of movement therein and so that said bearing member, with the bolt head inclosed therein, may be mounted in the boiler sheet in a manner to permit universal adjustment and to be subsequently secured to the boiler sheet, 25 preferably by welding.

With this and other objects in view, the invention consists in certain novel features in the method of making and installing staybolt structures for boilers, as hereinafter set 30 forth and pointed out in the claims.

The accompanying drawings illustrate the 40 steps of our improved method, and in said drawings, Figure 1 is a sectional view illustrating the staybolt structure as installed in a boiler, and Figs. 2 and 3 are views illustrating the manner of making the combined bearing plug and closure.

1 represents the outer sheet of a boiler and 45 2 the inner boiler sheet.

The outer boiler sheet is made with an opening 3 having a general tapering form and a portion of the wall of said opening may be rounded transversely of the thickness of the sheet to provide a seat 4 on which 50 a combined bearing plug or member and closure 5 may have an initial universally movable mounting.

The plug or member 5 may be made of a single piece of metal and may have the 55 spherical form shown in Figs. 1 and 3, with

an opening 5^a for the accommodation of the neck of the staybolt. The blank from which the plug or member 5 is made is provided with a plurality of V-shaped notches or recesses 6 and this blank is forged to the approximately hemispherical form shown in Fig. 2. The rounded head 7 of a staybolt 8 will be inserted into the hollow hemispherical body and inward pressure will be applied to the fingers 9 formed by the notches 6 until the side edges of said fingers come together as shown at 6^a and the tool employed for this operation will be such that the portion of the device formed by the fingers 9 will be curved in conformance with the curvature of the other portion of the device, 60 and the latter will have the form of a sphere except at the portion thereof having the opening 5^a for the passage of the bolt. The plug or member 5 has internal dimensions 65 which are appreciably greater than those of the bolt head 7 and when the latter is mounted on the seat 10 around and in proximity to the opening 5^a, ample clearance space 11 will be afforded for the bolt head, 70 75 and this is important in "flexible" staybolt structures.

The inner end portion of the staybolt is threaded as at 12 to screw through the inner boiler sheet, and said staybolt is provided 80 at its inner extremity with an angular head 13 to receive a tool whereby the screwing of the bolt through the inner boiler sheet may be facilitated. After the staybolt shall have been installed, the head 13 will be removed 85 and the inner end of the bolt will be upset as at 14. In order to assist in withstanding the end pressure on the bolt during the upsetting operation and to relieve the screw threads from excessive hammering pressure, 90 a body of soluble material 15, such as salt, may be packed in the clearance space within the hollow plug.

It will be observed that the plug or member 5 forms a closure for the opening in the 100 boiler sheet as well as a bearing member for the bolt head, and by mounting said member so that it may be universally movable, it can be adjusted in a manner to insure accurate alignment of the staybolt with its points of 105 connection with the respective boiler sheets, whether said sheets be parallel with each other or at an angle to each other, and when the combined bearing plug and closure shall have been properly adjusted, it will be 110

firmly united to the outer boiler sheet by means of a weld 16.

Having fully described our invention what we claim as new and desire to secure by Letters-Patent, is:—

1. The herein described method, consisting in notching a blank, forging said blank to form a hollow body having an opening, inserting the head of a staybolt into the hollow body, bending the notched portion of said hollow body inwardly to inclose the bolt head and provide a bearing within said hollow body for the bolt head, and leaving clearance space for the bolt head within said hollow body.
2. The herein described method, consisting in inclosing a bolt head within a hollow plug having a bearing for said bolt head, and having a clearance space for the bolt head, packing said clearance space with soluble material, threading the bolt through an inner boiler sheet, and upsetting the inner end of the bolt.
3. The herein described method consisting in notching a metal blank, forging said blank to form a hollow body closed at one

end and open at the other end, inserting the head of a staybolt into said hollow body, bending the notched portion of the hollow body inwardly and forming an interior 30 bearing for the bolt head and an exterior curved bearing surface for said hollow member in a bolt opening in a boiler sheet.

4. The herein described method consisting in permanently inclosing the head of a staybolt in a hollow body closed at one end and leaving a clearance space between the bolt head and the closed end of said hollow body, mounting said hollow body in an opening in an outer boiler sheet so as to close said opening and have initial universal adjustment therein, securing the bolt to an inner boiler sheet, and welding said hollow body to the outer boiler sheet.

In testimony whereof, we have signed this 45 specification in the presence of a subscribing witness.

ETHAN I. DODDS.
J. ROGERS FLANNERY.

Witness:

EDWIN S. RYCE.
